LUBRICANT DISPENSING APPARATUS

John M. Marshall and Edwin C. Thomas,
Pittsburgh, Pa.

Application January 13, 1934, Serial No. 706,501

9 Claims. (Cl. 221—47.1)

Our invention relates to improvements in lubricant dispensing apparatus, and more particularly to heating means therefor.

Automatic lubricant dispensers of large capacity, such as, for example, those employed as standard equipment in garages and automobile service stations, are generally operated either electrically or by means of compressed air.

Where it is necessary to operate the compressed air driven dispenser out-of-doors in the winter season, considerable difficulty has been encountered due to the hardening of the lubricant in the cold temperature, and the freezing of the air-operated parts of the device, particularly at the exhaust outlet.

It is a prime object of this invention to provide a heating means for such lubricant dispensers for effecting a ready and uniform flow of the lubricant, and to superheat the exhaust air to prevent ice formation and the resulting interruption of operation.

Additional objects are to provide a construction capable of ready application to and co-operation with present standard forms of air-operated lubricant dispensers; and to provide a construction having simplicity and low cost of manufacture.

Further objects will become apparent from the following description, taken in connection with the accompanying drawing, wherein:

Fig. 1 is a vertical sectional view of a lubricant dispensing apparatus embodying our invention;

Fig. 2 is a cross-sectional view taken on the broken line II—II of Fig. 1;

Fig. 3 is an elevational view of a portion of Fig. 1, showing a modified form of the invention; and

Fig. 4 is a similar view of a further modification.

Referring to the drawing, A designates generally a lubricant dispensing apparatus of well known form, for the high pressure dispensing of greases. Said device includes a grease tank or reservoir 5 having a bottom outlet 6 communicating with a working barrel 7 containing a reciprocable plunger 8.

Plunger 8 is mounted for reciprocation by means of a piston 9 within a cylinder 10, constituting an air-actuated grease pump, receiving and exhausting compressed air through a port 11 of said cylinder in alternate communication with an air inlet port 12 and an outlet or discharge port 13, controlled by an automatically operable slide valve 14, as will be readily understood. Air under pressure is supplied from any suitable source to the inlet port 12 by a pipe line 15.

In present practice, the plunger 8 expels a charge of grease from its barrel 7 and discharges said grease through a check valve 16 into an attached hose or conduit 17 which may be connected by any suitable means (not shown) to the part

or parts being lubricated. Rapid and repeated strokes of the plunger 8 build up high pressures on the grease against the obstruction of the said receiving part or parts.

The air exhaust port 13 of the pump in present equipment is open directly to the atmosphere. In cold weather, the air operating the pump is discharged at a temperature below the freezing point.

Any moisture in the exhaust air will collect in the exhaust pipe and about the port 13 as frost, almost instantly. Obviously, the resulting ice formation soon seals the exhaust port, making it necessary to shut down the dispenser and remove the ice. The low temperatures also affect the grease in the tank 5 and working barrel 7, thereby placing additional load and strain on the pump.

We have provided for the correction and elimination of these objectionable features by the application of a single heating means in the following manner.

The lubricant dispenser A is preferably enclosed within a heat insulating casing or cabinet 18 of any desired construction. For example, we have shown such a cabinet formed of wood with an exterior shell 19 of sheet metal and an interior lining 20 of asbestos, and including a removable cover 21. The connection for the hose 17 is extended outside of the cabinet 18 by means of a sleeve or nipple 22 threaded at its outer end to couple said hose and having threaded connection at its inner end with the working barrel 7 or its check valve 16.

In the design of the dispenser illustrated, the air exhaust of the pump takes place around a reduced end portion of the valve 14 extending within the exhaust port 13, which construction is enclosed within the cabinet 18 when applied. Means are provided in the form of a bonnet 23 for surrounding said port and introducing the exhaust air into a connected pipe or coil 24. The bonnet 23 may be secured in place in any suitable manner as by threads, screws, or the like.

Said pipe 24 is passed upwardly within the cabinet a substantial distance and is looped or coiled at its upper portion as at 25, returning downwardly and thence outwardly of the cabinet at 26 for final external air exhaust. A clamp or bracket 27 may be employed for securing the portion 25 of the pipe to a side wall of the cabinet, as shown.

Mounted within the cabinet 18 adjacent the air exhaust pipe 24, and preferably the looped or coiled portion 25 thereof, we provide a heating element 28. Said element may be of various types and styles in compliance with fire regulations.

We prefer to employ an insulated electric element, as a resistance unit, having electric con-

105
100
110
115
120

nections 29 with an external source of current 30 through an intervening switch or wall box 31. In Figs. 1 and 2, we have shown such element 28 in the form of a ring or disk supported from the 5 wall of the cabinet in close proximity to the exhaust pipe 24 by an insulator pin 32.

Hence, during the operation of the apparatus in low temperatures, the heat from the element 28 will pervade the interior of the cabinet 18 to warm 10 the grease contained in the tank 5, as well as that in the working barrel 7, and maintain a uniform flow thereof from the dispenser into the hose 17.

By reason of its close proximity to the exhaust pipe 24, or more specifically, the loop or coil 25 thereof, the element 28 will superheat the exhaust air passing therethrough, whereby said air will be discharged at 26 into the atmosphere at a much higher temperature than heretofore, thereby doing away with the undesirable formation of ice 20 at the outlet.

Likewise, incoming air of conduit 15 will be subjected to the heat of the interior of the cabinet, prior to entering the motor cylinder 10.

25 For the purpose of regulating the temperature of the interior of the cabinet 18, a thermostat device 33 may be electrically connected with the element 28 to control the same within certain desirable limits.

30 In Fig. 3, we have shown a modification embodying means for heating the incoming air prior to its introduction into the pump. In this form, a hollow cylindrical heating element 28a is employed in the same relation to the portion 25 of the exhaust pipe 24 as before, and having the air intake line 15a coiled about its exterior. Such construction further aids in superheating the air whereby it will be discharged at 26 at greatly increased temperature.

40 A still further modification is illustrated in Fig. 4, wherein a flat elongated electric heating element 28b is used, having the intake and exhaust pipes 15b and 24a disposed on either side of the element and extending longitudinally thereof. The element and adjacent pipe portions are enclosed within a metal case 34 filled with asbestos cement, whereby heat is transmitted to the air in said pipes for superheating the same, and heat is radiated from the case 34 of the entire assembly to heat the interior of cabinet 18 as before.

Further changes and modifications are contemplated within the scope of the following claims.

55 What we claim is:

1. In a lubricant dispensing apparatus, an air-actuated lubricant pump having air inlet and exhaust ports, a heat insulating cabinet enclosing said pump, an air exhaust pipe disposed within the cabinet having connection with the exhaust port and terminating outside said cabinet, and heating means disposed within the cabinet for heating the exhaust air in said pipe, as and for the purpose described.

60 2. In a lubricant dispensing apparatus, a lubricant reservoir, an air-actuated lubricant pump therefor having air inlet and exhaust ports, a heat insulating cabinet enclosing said reservoir and pump, an air exhaust pipe disposed within the cabinet having connection with the exhaust port and terminating outside said cabinet, and heating means disposed within the cabinet for heating the interior of the cabinet and the ex-

haust air in said pipe, as and for the purpose described.

3. In a lubricant dispensing apparatus, an air-actuated pump having inlet and exhaust ports, a heat insulating cabinet enclosing said pump, an air exhaust pipe having a substantial portion thereof disposed within the cabinet, said pipe having connection with the exhaust port and terminating outside said cabinet, an air inlet pipe disposed within the cabinet, and heating means in the cabinet positioned in close proximity to both of said pipes, for heating the incoming and exhaust air, as and for the purpose described. 80 85

4. In a lubricant dispensing apparatus, a lubricant reservoir, an air-actuated lubricant pump therefor having air inlet and exhaust ports, a heat insulating cabinet enclosing said reservoir and pump, an air exhaust pipe having a substantial portion thereof disposed within the cabinet, said pipe having connection with the exhaust port and terminating outside said cabinet, an air inlet pipe disposed within the cabinet, and heating means disposed in the cabinet in close proximity to both of said pipes, for heating the interior of the cabinet and the incoming and exhaust air in said pipes, as and for the purpose described. 90 95

5. In a lubricant dispensing apparatus, an air-actuated lubricant pump having air inlet and exhaust ports, a heat insulating cabinet enclosing said pump, a heating element disposed within the cabinet, and an air exhaust pipe connecting said exhaust port and having a portion thereof disposed within the cabinet in fixed relation to the heating element for heating the exhaust air in said pipe whereby said air is discharged outside the cabinet at a superheated temperature, as and for the purpose described. 105 110

6. In combination, an enclosing cabinet, a lubricant holder therein, a lubricant ejector in dispensing communication with the holder, an air-actuated motor having a supply and exhaust conduit leading into and out from the holder, a heater within the cabinet, and means subjecting circulating motor air to heater action within the 115 cabinet. 120

7. In combination, an enclosing cabinet, a lubricant holder therein, a lubricant ejector in dispensing communication with the holder, an air-actuated motor having a supply and exhaust conduit leading into and out from the holder, a heater within the cabinet, and means subjecting incoming motor air to heater action within the 125 cabinet.

8. In combination, an enclosing cabinet, a lubricant holder therein, a lubricant ejector in dispensing communication with the holder, an air-actuated motor having a supply and exhaust conduit leading into and out from the holder, a heater within the cabinet, and means subjecting outgoing motor exhaust air to heater action within the cabinet. 130 135

9. In combination, an enclosing cabinet, a lubricant holder therein, a lubricant ejector in dispensing communication with the holder, an air-actuated motor having a supply and exhaust conduit leading into and out from the holder, a heater within the cabinet, and means subjecting incoming motor supply air and outgoing motor exhaust air to heater action within the cabinet. 140 145
